(57) **CLAIM**

The ornamental design for a pair of display screens with animated graphical user interface, as shown and described.

DESCRIPTION

Pair of display screens with animated graphical user interface

4.1 is the front display screen of a pair of display screens with an animated graphical user interface, showing the first image in a sequence;

4.2 is a back display screen of a pair of display screens with an animated graphical user interface, showing the second image thereof;

4.3 is the front display screen, showing the third image in the sequence; and

4.4 is the back display screen, showing the fourth image in the sequence.

The appearance of the transitional images sequentially transition between the images shown in Reproductions **4.1** through **4.4**. The process or period in which one image transitions to another image forms no part of the claimed design.

The broken line perimeter in Reproductions **4.1** and **4.3**, and the broken line perimeter in Reproductions **4.2** and **4.4**, show two separate display screens and form no part of the claimed design. The broken lines within the display screens illustrate portions of the animated graphical user interface and form no part of the claimed design.

Shaded portions in the figures show a contrast in appearance with the non-shaded claimed portions. The shading in Reproductions **4.3** represents the appearance of translucency.

The central white button in FIGS. **4.1** and **4.4**, and the white icons and “X” in FIG. **4.3**, show opaque tonal white and form part of the claim. All other white areas show portions of the graphical user interface that form no part of the claim.
